Fig. 5.

UNITED STATES PATENT OFFICE.

CHARLES A. HULTQUIST, OF LOS ANGELES, CALIFORNIA.

PNEUMATIC DRILL.

Application filed August 14, 1922. Serial No. 581,633.

To all whom it may concern:

Be it known that I, CHARLES A. HULTQUIST, a citizen of the United States, residing at Los Angeles, in the county of Los

10 Angeles and State of California, have invented a new and useful Pneumatic Drill, of which the following is a specification.

This invention relates to rock drills of the fluid operated type, and more especially to 10 that type employing a water tube.

In pneumatic drills employing water tubes, said tubes are subject to breakage or clogging, and, in either event, the water tube must be removed and repaired or another 15 one substituted for it. In order to remove the tube it is necessary to take the machine apart, and it will be readily understood that, if this is done in the mine with drills having air ducts exposed at the joint where 20 the parts are separated, dust, always present in the mine, will collect on the members forming the joint and small particles of rock fall into the air feed control port and lodge between the wall of the feed cylinder and 25 the cup leather, doing injury to both.

Because of liability to injury by dust when the repair is made in the mine, it has been customary and practically necessary to hoist the drilling machine to the surface of the 30 earth and have the repair made in a shop. This hoisting of the machine to the surface causes a considerable delay to the mining operations and also delays the hoisting machinery in performing other necessary operations, thus increasing the mining costs. 35

An object of this invention is to make it possible to replace or clean the water tube in the mine without liability of the mine dust getting into the drill and interfering 40 with the effective operation thereof.

The accompanying drawings illustrate several forms of the invention:

Figure 1 is a longitudinal view of a pneumatic drill constructed in accordance with 45 the provisions of this invention, a portion of the drill steel being broken away.

Fig. 2 is an enlarged fragmental section on the line indicated by 2-2 Fig. 1, the joint between the valve block and feed leg being closed. 50

Fig. 3 is a sectional view similar to Fig. 2, with the joint open, so that the water tube can be removed.

Fig. 4 is a longitudinal view of the valve 55 employed in the drill shown in Figs. 1 and 3.

Fig. 5 is a plan view of a modified construction, looking at the upper end of the valve block, the hammer cylinder being omitted. 60

Fig. 6 is a sectional elevation on the line indicated by 6-6 Fig. 5.

Fig. 7 is a longitudinal view of the valve employed in the modified construction 65 shown in Figs. 5 and 6.

Describing first the form of the invention shown in Figs. 1 to 4, the valve block is indicated at 8 and is secured by bolts 9 or other suitable means to the cylinder 10. In the cylinder 10 is the usual hammer 50. Extending transversely of the valve block 8 is a cylindrical chamber 11 in which is positioned a rotary valve 12. The valve chamber 11 communicates through a port 13 with the bore 14 of the cylinder 10. Thus when the valve 12 is appropriately turned it permits the operating fluid to flow from the feed pipe 15 through the axial valve bore 28 and port 16 of the valve and through the port 13 to the cylinder bore. 75

The valve block 8 seats against the upper end of a feed cylinder 17 which contains the usual plunger 18 operated by compressed fluid in the cylinder 17 to feed the drill so that the drill steel will be forcibly pressed against the rock being operated upon. In order to supply the feed cylinder 17 with compressed fluid, it has heretofore been customary to pass the fluid from the valve chamber 12 directly to the feed cylinder 17, 90 the port for carrying the fluid passing from the valve block into the upper end of the feed cylinder across the joint 19 between the valve block and the feed cylinder. In order to avoid the necessity of having the port exposed to dust, when the joint between the valve block and feed cylinder is broken, I have provided two different constructions, one of which, disclosed in Figs. 1, 2 and 3, 95 will now be described.

The feed cylinder 17 is provided with an ear 20 inserted between a pair of ears 21 projecting from the valve block 8. Extending through the ears 20, 21 is a bolt 22 which constitutes a pivot or pintle, thus hinging the valve block to the feed cylinder. The pintle 22 is provided with a duct 23 which extends for a portion of its length axially of the pintle and is disposed at its opposite ends transversely of the axis. One end of the duct 23 communicates with a duct 24 in the ear 20, said duct 24 communicating with 100 105 110 115

the bore of the cylinder 17. The other end of the duct 23 communicates with a duct 25 in one of the ears 21, said duct 25 communicating with the valve chamber 11. When 5 the valve 12 is in the position shown in Fig. 2, the duct 25 communicates with a duct 26 extending longitudinally of the valve and said duct 26 at the same time registers with a port 27 opening through the wall of the 10 valve chamber to the atmosphere. This, as will be clearly understood, permits discharge of operating fluid that may be in the feed cylinder 17.

The bore 28 of the valve is provided with 15 a port 29 communicating with a duct 30 extending circumferentially of the valve 12. When the valve is turned to register the port 16 with the port 13, the duct 30 registers with the duct 25 so that not only is the 20 operating fluid admitted to the cylinder 10 but also to the feed cylinder.

A water tube is shown at 31 and is packed in the usual manner by packing 32 contained in a recess 33 in the valve block 8. The 25 packing 32 surrounds the tube 31 between one end of the recess 33 and a shoulder 34 on the water tube. Bearing against the shoulder 34 is a plug 35 which is screw-threaded into the valve block, thus detachably holding 30 the water tube in place. The water tube 31, as is customary, extends through the hammer as seen in Fig. 1. The water tube is supplied with water through a duct 311 in the valve block and furnishes water to the drill, 35 not shown, in a manner well understood in this art.

On the side of the valve block opposite the valve is a longitudinal slot 36 in which is pivoted a latch bolt 37, the pivot being indicated at 38. The bolt is adapted to extend 40 through a slot 39 in the feed cylinder 17, and the nut 40 of said bolt is adapted to bear against the feed cylinder to releasably hold the valve block closed upon the feed cylinder. When the bolt 37 is released, the feed block may be thrown back at right angles to the axis of the feed cylinder so that 45 the operator may readily unscrew the plug 35 and remove the water tube 31.

It is particularly noted that when the 50 valve block is in the open position shown in Fig. 3 it is as impossible for dust to have access to the various ducts that connect the valve chamber with the feed cylinder, as when the block is in the closed position shown in Fig. 2. Thus mine dust cannot be entrained by the operating fluid and get into the bore of the feed cylinder between the 55 wall and the plunger.

Now referring to Figs. 5, 6 and 7, showing the modified form of the invention, the parts corresponding to those shown in Figs. 1 to 4 are indicated by the same reference characters with the addition of a prime mark and such parts will not be again de-

scribed since a full description has been hereinbefore given. The construction in Figs. 5 to 7 differentiating from that shown in Figs. 1 to 4 is as follows:

The valve block 8' is provided with an ear 70 41 through which extends a bolt 42 constituting a pintle or pivot whose axis is parallel with the longitudinal axis of the feed cylinder 17'. The pintle 42 also extends through an ear 43 of the feed cylinder 17'. The pintle 42 is provided with a duct 44, a portion of which extends axially of the pintle and the end portions of which extend transversely thereof. The duct 44 communicates with a duct 45 opening into the valve 80 chamber 11'. The other end of the duct 44 communicates with a duct 46 opening into the bore of the feed cylinder 17'. When the valve 12' is in the position shown in Fig. 6 the duct 45 communicates with a duct 47 extending lengthwise of the valve and at the same time said duct 47 communicates with a port 48 opening through the wall of the valve chamber to the atmosphere.

When the valve 12' is in position to register the port 16' with the port 13' the duct 45 registers with a duct 51 extending circumferentially of the valve 12', said duct 51 communicating with the valve bore through a port 52.

To gain access to the water tube 31' the latch bolt 37' will be released and the valve block will then be swung laterally on its pintle 42. It will now be clear that the only difference between the two forms of the invention is that in the drill shown in Figs. 1 to 4 the valve block opens in a plane extending longitudinally of the axis of the drill, whereas in the form illustrated in Figs. 5 to 7 the valve block opens in a plane extending transversely of the axis of the drill.

I claim:

1. In a pneumatic drill, the combination of a valve block having a water supply duct, a cylinder connected with the valve block, a hammer in the cylinder, a water tube receiving water from said duct and extending through the hammer and detachably engaging the valve block to supply water to the drill, a feed cylinder hingedly connected to the valve block, the hinge connection having a duct, the feed cylinder having a duct connecting its bore with the second duct, the valve block having a valve chamber and having a duct connecting said chamber with the second duct, there being a port in the valve block connecting the valve chamber with the bore of the first cylinder, a plunger in the feed cylinder, a valve in the valve chamber controlling the port and the duct in the valve block, and means to hold the valve block closed upon the feed cylinder.

2. In a pneumatic drill, the combination of a feed cylinder, a valve block hingedly connected to the feed cylinder, and a valve

mounted in the valve block, there being an air passage controlled by the valve and extending through the hinge connection and communicating with the bore of the feed cylinder.

3. In a pneumatic drill, the combination of a feed cylinder, a valve block, a pivot connecting the valve block to the feed cylin-

der, and a valve mounted in the valve block, there being an air passage controlled by the valve and extending through the pivot and communicating with the bore of the feed cylinder.

Signed at Los Angeles, California, this 3d day of August, 1922.

CHARLES A. HULTQUIST.
